CLAIM

I claim, the ornamental design for an arrowhead case, as shown and described.

DESCRIPTION

FIG. 1 is a top and front perspective view of an arrowhead case, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is perspective view thereof, shown in an opened configuration; and,

FIG. 9 is a bottom perspective view of the arrowhead case.
